UNITED STATES PATENT OFFICE.

ELMER E. HENDRICKS, OF KLAMATH FALLS, OREGON.

SPRING SHACKLE.

Application filed January 20, 1922. Serial No. 530,686.

To all whom it may concern:

Be it known that I, ELMER E. HENDRICKS, citizen of the United States, residing at Klamath Falls, in the county of Klamath 5 and State of Oregon, have invented certain new and useful Improvements in Spring Shackles, of which the following is a specification.

The present invention relates to a spring 10 shackle device or shock absorber, and has for its object to provide a device of this character which embodies novel features of construction whereby two elements such as the sections of a spring can be yieldably 15 connected in a very efficient and satisfactory manner.

Further objects of the invention are to provide a device of this character which has a strong and rugged construction so that it 20 will successfully withstand the hard usage to which such contrivances are subjected in actual practice, which is comparatively simple and inexpensive in its construction, and which functions as a cushioning or shock 25 absorbing device in a most satisfactory manner.

With these and other objects in view, as 30 will more fully appear as the description proceeds, the invention consists in certain combinations and arrangements of the parts, the novel features whereof are pointed out in the appended claims.

For a full understanding of the invention, reference is to be had to the following 35 description and accompanying drawings in which:

Figure 1 is a side elevation of a spring shackle device which is constructed in accordance with the invention.

Figure 2 is a similar view with the spring elements appearing in section.

Figure 3 is a vertical sectional view on the line 3—3 of Figure 2.

Figure 4 is a detail view of one of the 45 eyes.

Figure 5 is a transverse sectional view on the line 5—5 of Figure 2.

Figure 6 is a detail view of the blank 50 from which the multiple volute spring element is formed.

Corresponding and like parts are referred to in the following description and indicated in all of the views of the drawings by like reference characters.

Referring to the drawings, which illustrate 55 one possible embodiment of the inven-

tion, the numerals 1 designate the pins or bolts which are utilized for attaching the eyes 2 of the cushioning device to the spring sections or other objects which are to be 60 yieldably connected. The eyes 2 are arranged in pairs and are formed with stems 3 which are engaged by the ends of volute spring elements 4.

These volute spring elements are also arranged in pairs, the elements of each pair being substantially co-axial and the axes of the two pair of spring elements being substantially parallel. The spring elements are formed by bending the arms formed by 70 the bifurcated ends of a spring bar or strip 5, such as that which is shown in detail by Figure 6. The middle portion of the strip 5 forms a cross bar or brace which connects the two pair of volute springs and tends to 75 hold them in proper position relative to each other. This is a very simple and inexpensive manner of forming the spring device and the springs have a rugged construction which enables them to withstand heavy 80 stresses and to function properly as cushioning devices under difficult circumstances.

The smaller ends of the volute spring elements are secured to the stems 3 of the 85 respective eyes 2. For this purpose the stems 3 may be bifurcated, as indicated at 3^a and one of the arms of the bifurcation may be narrower than the other arm by an amount equal to the thickness of the spring device, as indicated quite clearly by Figure 90 5, so that the end of the spring arm may be wound snugly around the stem and the extremity thereof deflected laterally and secured within the bifurcation 3^a. A depression or slot 6 may be provided at the base 95 of the bifurcation to receive and interlock with the spring arm and the spring may be secured to the stem in any suitable manner, such as by welding or by means of a pin 7.

The eyes 2 at opposite ends of the shock absorbing device receive the pins or bolts 1 which serve as means for attaching the device to the spring sections or other elements to be connected by the shackle, and the bolts 1 may be formed with angular 105 heads which are engaged by lugs 8 upon corresponding eyes 2 to lock the bolts against rotation. The opposite ends of the bolts may have openings 9 therein which are adapted to receive cotter pins or the like to retain the bolts in position. The volute spring elements 4 are arranged in 110

such a manner that the members engaged by the bolts 1 are yieldably connected and shocks and jars will be effectively absorbed by the shackle. The inner ends of opposed stems 3 will engage with each other and form stops to limit further movement when the springs are compressed to their full capacity.

While I have described one particular embodiment of the invention in detail for illustration purposes, it will be understood that many modifications and changes can be made in the details of construction without departing in any manner from the spirit of the invention.

Having thus described my invention what I claim as new and desire to secure by Letters Patent, is:

1. A shackle device of the character described, comprising a plurality of sets of complementary volute spring elements arranged side by side, the spring elements of each set having an opposed relation and a common axis, and means for connecting the outer ends of the volute spring elements directly to the vehicle springs, whereby the volute spring elements of the shackle device will be interposed between the parts connected by the shackle.
2. A shackle device of the character described, comprising a plurality of complementary sets of volute springs arranged side by side, connecting means between the sets of volute springs, and common attachment means for the corresponding ends of the different sets of springs.

3. A shackle device of the character de-

scribed, including a spring strip having the opposite ends thereof bifurcated to form diverging arms which are bent to form volute spring elements arranged in pairs and the elements of each pair having an opposed relation, and attachment means associated with the spring elements.

4. A shackle device of the character described, including a plurality of complementary sets of volute spring elements, the elements of each set having an opposed relation and a substantially common axis, attachment eyes detachably connected to the outer ends of the volute spring elements, and attachment bolts engaging the opposite sets of eyes.

5. A shackle device of the character described, including a spring strip having the ends thereof bifurcated to form diverging arms which are bent to provide volute spring elements, said spring elements being arranged in opposed pairs, attachment eyes secured to the volute spring elements, and attachment bolts engaging the opposite sets of eyes.

6. A shackle device of the character described, including a pair of oppositely extending volute springs connected at their inner ends, and attachment members at the outer ends of the volute spring, said attachment members being formed with bifurcated stems around which the spring arms are bent, the extremities of the arms being anchored within the bifurcations.

In testimony whereof I affix my signature.

ELMER E. HENDRICKS.
